UNITED STATES PATENT OFFICE.

GARFIELD A. WOOD, OF ALGONAC, MICHIGAN.

DRIVING MECHANISM FOR TRUCK-BODY HOISTS.

1,325,661.

Specification of Letters Patent. Patented Dec. 23, 1919.

Application filed December 23, 1918. Serial No. 268,008.

To all whom it may concern:

Be it known that I, GARFIELD A. Wood, a citizen of the United States, and residing at Algonac, in the county of Macomb and 5 State of Michigan, have invented a new and Improved Driving Mechanism for Truck-Body Hoists, of which the following is a specification.

The present invention relates to motor vehicles, more particularly to means whereby 10 an auxiliary mechanism or element, such as the pump of a hydraulic body-tilting unit, may be driven from the transmission, and it is in the nature of an improvement over 15 those described and claimed in my applications for U. S. Letters Patent S. N. 142,405, filed Jan. 15, 1917, and 176,459 filed June 23, 1917. Its aim is to provide means of such nature as to permit of use with a minimum 20 change in the various installations found in practice.

It will be understood that the body tilting unit is generally furnished by one manufacturer whereas the truck chassis to which it 25 is to be applied are built by many different parties, and vary widely in size, proportion and relation of essential parts.

The invention consists in a transmission casing having a removable casing element 30 through which access to the interior may be had and a gear carried by the casing element and driven by a gear on the countershaft of the transmission, through which power may be applied for driving a hoisting mechanism or the like, such, for example, as the pump of a hydraulic body tilting mechanism.

Again, the invention consists in a transmission casing having a countershaft projecting therefrom and carrying a gear exterior to the casing in combination with a gear housing separate from the casing and mounted thereon and carrying a gear driven by the countershaft gear; it also consists in 45 a hydraulic hoisting mechanism comprising a pump support depending below the upper edge of the side bars of a truck and carrying a pump driven by the last named gear together with means supported by the pump 50 support for establishing driving connection between the gears at will.

Another feature of the invention lies in the provision of a gear housing which may be attached to the transmission casing, in 55 various positions of angular adjustment

about the axis of the countershaft, whereby the device is rendered applicable to different installations wherein clearance may not always be available when the parts are assembled in the same angular relation. 60

The invention also consists in certain means for attaching the countershaft gear to the countershaft whereby the gear may be readily accommodated to projecting countershaft ends of different lengths. 65

The invention further consists in various details of construction and relationships of parts shown, described and pointed out in the claims.

In the drawings, Figure 1 is a side view 70 showing a dump vehicle wherein the invention is embodied. Fig. 2 is an enlarged fragmentary section on about the line 2—2 of Fig. 1. Figs. 3 and 3^a are similar sections, the pump being differently arranged. 75 Fig. 4 is a longitudinal section corresponding to Fig. 2, parts being broken away. Fig. 4^a is a section on the line 4^a—4^a of Fig. 4, parts being broken away. Fig. 5 is a longitudinal section showing the preferred 80 manner of attaching the driving gear to the end of the transmission countershaft. Fig. 6 is a view looking from the right in Fig. 5. Fig. 7 is a plan view corresponding to Fig. 4. Fig. 8 is an enlarged fragmentary 85 view on about the line 8—8 of Fig. 4. Fig. 9 is a side view corresponding to Fig. 8, parts being broken away. Fig. 10 is a fragmentary longitudinal section, parts being broken away, showing a modification. Fig. 90 11 is a fragmentary transverse section on the line 11—11 of Fig. 10.

Referring particularly to Fig. 1, 1 indicates the frame of a motor vehicle on which the body 2 is tiltable about pivots 3 by 95 means of the hydraulic jack or hoist 4. The usual internal combustion engine appears at 5, and connected thereto is the transmission casing 6 from which the engine shaft projects rearwardly at 7 for connection to the propeller shaft 8 by means of the universal joint 9. The transmission casing also carries a countershaft (Fig. 4) the rear end 10 of which projects out through a removable casing section consisting, in 100 this instance, in a gland or gland cover 11 which is finished at 12 to bear on the rear wall of the casing and has the reduced tapering portion 13 and is detachably secured to the casing, preferably by means of cap 110

2
screws 14 equally spaced angularly about the shaft 10. In the embodiment shown, the front cross bar 18, whereon the base 19 of the hoisting cylinder rests, carries the depending member 20, preferably of angle iron, on the lower end of which the gear pump 21 is mounted by means of the cap screws 22, said pump serving to draw oil from the upper end portion of the cylinder through the suction pipe 23 and expel it into the base thereof through the pressure pipe 24. The parts thus far described are of well known construction, it being understood, however, that the member corresponding to the element 11-13 and found in initial equipment may have to be replaced by another having a tapering neck 13 of proper shape and size.

The shaft 10 has a reduced end portion 28, Fig. 5, of non-circular cross-section, the length, shape and size of which may vary considerably in the different makes of transmissions; moreover, the material of which these shafts are made is ordinarily hard and difficult to work which, together with other considerations, renders it inadvisable to make any change in the shaft after the transmission is completed. The shaft is also tapped to receive a cap screw 29. For reasons which will be more fully pointed out hereinafter, it is desirable to secure a gear on said shaft end at a predetermined distance from the surface 12 and, while this may be done in different ways, I prefer to provide a bushing 30 which is adapted to be clamped against the shoulder 31 by means of the cap screw 29, washer 32 and lock washer 33, and which is of an external diameter corresponding to the internal diameter of a gear 34. By cutting off the front end of the bushing to a proper length and by drilling a series of keyways 35 therein to a proper depth, and by thereafter peening or pressing the metal of the bushing over on the front face of the gear at 36 and pressing the ends of the keys 37 at 38-39, it is evident that the gear is rigidly and readily secured in place. That is, all changes necessary to properly position the gear 34 are made by variations in the bushing, and are of a nature that permits the work to be done without special equipment.

Surrounding the neck 13 and retained thereon by the same cap screws 14 which hold the element 11-13 in place on the transmission casing is a ring 40 that constitutes a base for and is formed integrally with a gear housing 41 wherein two alined bearings 42-43 for the shaft 44 are carried. Preferably the front end of the bearing 42 is closed at 45 by the housing, and the bearing 43 is held in place by the nut 46, while lubrication is attained through the medium of grease cups 48. The shaft 44 carries a gear 49 keyed or otherwise fixed thereon

and is shiftable longitudinally of the gear 34 to engage or disengage the gear 49 therefrom at will.

The driving shaft for the pump gears appears at 50, (Fig. 4); it projects into and supports a hollow shaft section 51 slidably thereon but non-rotatable in respect thereto, and the latter has the spherical end 52 through which the cross bolt 53 passes. In a somewhat similar manner the shaft 44 is received in a hollow shaft section 54 rigidly secured thereon—as by means of a key 55 and set screw 56—and having its spherical rear end 58 traversed by the cross bolt 60. In applying the device to the different truck installations, the distance from the pump to the transmission is subject to considerable variation, a condition which is conveniently met by simply cutting off one end of the tubing or hollow shaft section 61 to proper length. It will be understood that the holes 62-63 formed in the tubing for the cross bolts are of somewhat larger diameter than the latter, thus allowing universal movement at each joint.

Various means may be employed for establishing and breaking driving connection between the parts. I prefer, however, to shift the shafting bodily and preferably employ for this purpose a yoke 65 the arms of which have end portions 66 that travel in the groove 68 in the section 51. At its opposite end 69, the yoke is preferably spherical and is supported for play in all directions in the bracket or housing 70 which is attached to the member 20 by cap screws 71; the mid-portion of the yoke is reduced at 72 and is embraced by the divided end 73 of an operating lever 74 that is, in turn pivoted on the bracket 70 at 75, Fig. 4. In case space is not available for the lever in the position shown, it may be pivoted to the bracket at 76, (see Fig. 10) but it is desirable, in any event, that the parts be so arranged as to cause the weight of the upwardly extending operating link 78, should the latter be shaken free in traveling, to tend to maintain the gears disengaged.

It will be observed that the control means for establishing or breaking driving relation between the shafts 10 and 44 is independent of any control means for the various gears (not shown) of the transmission proper.

Space not being available in some instances for locating the pump as shown in Fig. 2, it may be placed in the manner indicated in either Fig. 3 or 3^a, the change being readily accommodated by shifting the housing 41 ninety degrees about the axis of the shaft 10, which is permitted by the equal angular spacing of the cap screws 14.

In the embodiment of the invention which appears in Figs. 10 and 11, the transmission casing 80 is finished opposite a reverse idler or other gear 81 on the countershaft 82 to

form an opening which may be closed by a cover plate (not shown, but held in place by cap screws 83) in the event it is not desired to drive an auxiliary unit. Upon removing the cover plate it is evident that the cap screws 83 may be utilized to likewise secure the supplemental gear housing 84 wherein the shaft 85 and gear 86, that correspond to the shaft 44 and gear 49, are slideable and rotatably mounted. The gear 81 and countershaft 82 correspond to the gear 34 and shaft 10, and the remaining parts may be duplicates of similar elements heretofore described and are therefore given the same reference characters.

The constructions described are inexpensive, easily applied, and admirably meet the many different conditions encountered in practice, and while I regard them as the most desirable embodiments of my invention, it is obvious that many changes may be made without departing from the spirit of my invention; for example, the number 11-13 may in some cases be integral with the element 41. I do not, therefore, wish to be limited except as indicated by the subjoined claims.

I claim:

1. A motor vehicle comprising a frame, a gear box, a rotatable countershaft for the gear box, a rotatable member spaced from the gear box longitudinally of the frame, means, independent of the gear box for supporting the rotatable member from the frame, shafting through which torque for driving the rotatable member from the countershaft is transmitted, a gear on the countershaft and a second gear on the shafting adapted to mesh with the first named gear, housing means for the second gear supported by the gear box, and means, carried by the means for supporting the rotatable member, for shifting one of said gears to or from mesh with the other at will.

2. In combination with the frame of a motor vehicle and a support extending across the frame and depending therefrom, a pump carried by the support, a transmission forward from the support and including a casing and a countershaft gear, a second gear adapted to mesh with the countershaft gear, shafting for driving the pump from the second gear, and means, including a lever carried by the support, for shifting the second gear to or from mesh with the countershaft gear at will.

3. In a motor vehicle, a transmission, a cross-support spaced from the transmission longitudinally of the vehicle and including a depending element, a pump carried by said element on one side thereof, said pump including a casing, a shaft projecting therefrom longitudinally of the vehicle, the transmission including a rotatable driving member, longitudinally shiftable means

through which driving connection between the driving member and the pump shaft may be effected at will, a lever of the second class pivotally supported by the depending element and having its free end directed toward the pump, and a second lever engaging the first mentioned lever intermediate its ends for shifting said shiftable means to make or break said driving connections at will.

4. In combination with a frame of a motor vehicle and a cross-support on said frame, said cross-support including a depending element, a pump fixed to one side of said element, a bracket separate from the pump and also carried by said element, said pump including a projecting shaft, means for driving said shaft, means for controlling said shaft driving means, said controlling means including a lever of the second class having one end bearing in said bracket, and a second lever engaging the first mentioned lever at a point intermediate in the length of the latter.

5. In a motor vehicle, a transmission casing having a countershaft projecting therefrom, a gear on the countershaft exterior to the casing, a detachable casing section through which which the countershaft passes, said section being constructed and arranged to be secured to the casing in any one of a plurality of positions angularly about the axis of the countershaft, a shaft carried by said casing section and offset from the countershaft, and a gear on the offset shaft meshing with the gear on the countershaft.

6. In a motor vehicle, a transmission including a countershaft and a casing, said casing including a removable element through which the countershaft passes, a gear on the countershaft outside of said element, housing means rigid with said element, a shaft carried by the housing means and having a gear thereon, said gear being adapted to mesh with the gear on the countershaft.

7. In combination with a transmission proper including a casing and a driving shaft supported thereby and projecting therefrom, a gear housing, means for detachably securing the housing on the casing, said means being so constructed and arranged that the housing may be secured in any one of a plurality of positions angularly about the axis of the shaft, a second shaft carried by the housing, a gear on the second shaft, and a gear on the first shaft meshing with the gear on the second shaft.

8. In combination with a transmission casing and a driven shaft projecting therefrom, a gear mounted on the shaft exterior to the casing, a gear housing detachably secured to the casing, a shaft supported by the housing and shiftable parallel to the first named shaft, a gear on the second shaft

adapted to mesh with the first gear or to be disengaged therefrom depending on the position of the second shaft.

9. In combination with a transmission casing having an opening in one wall thereof, a driven gear therein registering with said opening, a detachable gear housing mounted on the casing around the opening, a shaft carried by the housing, a gear on

said shaft adapted to be brought into mesh 10 or shifted out of mesh with the first named gear, shafting driven by said shaft and having universal movement in respect thereto, and means, acting through said shafting, for shifting the second mentioned gear to 15 or from mesh with the first gear at will.

GARFIELD A. WOOD
